FILM CASSETTE

Max Steinberg, Lake Success, Arthur Elian, Great Neck, Louis Verrone, Pearl River, and Roger Klingenberg, Stony Point, N.Y., assignors to Apex Photoletter Composing, Inc., Great Neck, N.Y.

Filed June 29, 1970, Ser. No. 23,704

Term of patent 14 years

Int. Cl. D16—99; D14—02
U.S. Cl. D61—1

FIG. 1

FIG. 4

FIG. 2

FIG. 3

FIG. 5

FIG. 6

FIG. 1 is a top view of a film cassette showing our new design;

FIGS. 2 and 3 are the side views thereof showing a protruding annulus, a recessed inwardly tapering central hub, and abutting webs on each side of the film cassette;

FIG. 4 is a front view of the film cassette showing an open mouth adjacent the top surface of the film cassette;

FIG. 5 is a rear view of the film cassette; and

FIG. 6 is a bottom view of the film cassette showing sockets formed from the webs adjacent the bottom surface of the film cassette.

We claim:

The ornamental design for a film cassette, substantially as shown and described.
